UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR AN ARTICLE OF MANUFACTURE.

54,328.

Specification for Design. Patented Dec. 23, 1919.

Application filed July 23, 1919. Serial No. 312,843. Term of patent 7 years.

To all whom it may concern:

Be it known that I, HAROLD E. NOCK, a citizen of the United States, residing at Newburyport, in the county of Essex and State of Massachusetts, have invented a new, original, and ornamental Design for an Article of Manufacture, of which the following is a specification, reference being had to the accompanying drawing, forming a part thereof.

In the accompanying drawing there is shown a representation of a circular plate, embodying the new design.

In the drawing the design is shown on but a portion of the border of the plate, but it will be understood that it is continuous around the border, as suggested by the dotted lines in the drawing.

The design comprises an ornamental decoration having the configuration and characteristics delineated, and, as shown, is embodied in a plate through application to its border, but it is contemplated that the design may, in like manner, also be embodied in or applied to various other analogous articles of hollow-ware.

It will be understood that the shape, or configuration of the article of hollow-ware in which the design is shown, as embodied, is not novel.

What is claimed, is:—

The ornamental design for an article of manufacture as shown and described.

HAROLD E. NOCK.
